UNITED STATES PATENT OFFICE.

EUGENE L. BARNES, OF BUFFALO, NEW YORK, ASSIGNOR TO THE BARBER ASPHALT COMPANY, OF PHILADELPHIA, PENNSYLVANIA, A CORPORATION OF WEST VIRGINIA.

REFRIGERATING APPARATUS.

Application filed July 20, 1926. Serial No. 123,641.

My invention relates to refrigerating apparatus, and more particularly to apparatus for developing and utilizing the refrigerating effect from the working substance or refrigerant;—e. g., the “evaporator and cooler” of systems operating on the compression-condensation-vaporization cycle. I aim to provide a simple, convenient, compact, efficient, and inexpensive vaporizing and cooling device. My invention is particularly adapted and advantageous for “flooded” systems, as they are commonly termed, in which a body of liquid in the low pressure side of the system gradually vaporizes or “boils” as it absorbs heat from the region or article that it is desired to refrigerate. I have here shown and described an embodiment of the invention suitable for insertion in a refrigerating box or compartment such as the ice chamber of an ordinary household refrigerator.

In the drawings, Fig. I is a front-end elevation of a device or apparatus conveniently embodying my invention.

Fig. II shows a vertical longitudinal section through the apparatus, taken as indicated by the line II—II in Fig. I.

Fig. III is a plan view with the upper portion of the apparatus in horizontal section as indicated by the line III—III in Fig. I.

Fig. IV is a rear view, showing the apparatus in vertical section as indicated by the line IV—IV in Fig. II.

As here shown (Fig. I, especially), the apparatus comprises a casing 1 of substantially rectangular form whose lower portion, at least, is adapted to serve as an ice-forming or freezing-compartment. Above the freezing compartment afforded by the casing 1 is a refrigerant chamber or drum 2, here shown as cylindrical and as arranged horizontal and lengthwise of the casing 1.

In the present instance, the drum 2 is enclosed in the upper portion of the casing 1, whose walls slope upward and inward and connect over the top of the drum in a curved “roof”. As shown in Figs. II, III, and IV, the side walls of the casing 1 are provided with internal supporting guides 3, preferably in the form of lugs, for the flanged margins of the trays 4. The rear wall of

the casing 1 is provided with end-stops 5 for limiting the inward sliding movement of the trays 4 on the lateral guides 3. For convenience in making various connections thereto, the front end wall 6 of the drum 2 (which also serves as a portion of the front end wall of the casing 1) may be made of comparatively heavy metal, while the other portions of the casing 1 and of said drum 2 may be of comparatively thin sheet metal. The lower portion of the casing 1, where the trays 4 are mounted, is provided with a removable closure or door 7, hinged at 8 to swing forward and upward to afford free access to the tray 4 and the interior of the casing 1. Preferably, the rear end of the drum 2 projects a short distance outside of the casing 1, through the upper portion of its rear wall.

At opposite sides of the casing 1 are cooling devices or units, shown as consisting of tube banks exposed at the exterior of the casing to the atmosphere surrounding the refrigerating device, and arranged against the side walls of the casing 1. Each of these tube banks has a (cylindrical) upper header 10 with upright tubes 11 depending therefrom and connected at their lower ends into a (cylindrical) lower header 12. The headers 10, 10 and 12, 12 are located above and below the upper and lower corners of the casing 1, so as to let the tubes 11, 11 lie in direct thermoconductive contact with the casing. As shown in Figs. I and IV, the upper headers 10, 10 are at either side of the drum 2 at a corresponding level, so that for a normal level of liquid refrigerant in the apparatus which will leave a substantial free space in the top of the drum 2, the free surface of the liquid in the lateral cooling units will be in the headers 10, 10. A suitable liquid level is indicated in dotted lines in Fig. IV. As shown in Figs. II, III, and IV, there are downflow and equalizing connections from the drum 2 to the lower headers 12, 12, in the form of tubes 13, 13 connected into the lower side of said drum and into the upper portion of said headers at their rear ends outside the casing 1. The vapor spaces in the top of the drum 2 and of the upper headers 10, 10 are shown connected by curved tubes 14, 14 that take into the tops of

said drum and headers about at the middle (Fig. II). The banks of tubes 11, 11 may be secured against the sides of the casing 1 by means of tie-rods or stays 15, 16 that 5 interconnect tie-bars or clamp-plates 17 engaged on adjacent tubes. As shown, there are a couple of stays 15, 15 near the upper ends of the tubes 11, 11, extending across through the interior of the casing 1 just below the drum 2, but well above the space 10 occupied by the trays 4 (Figs. II, III, and IV). There are also a couple of stays 16, 16 at the lower ends of the tubes 11, 11, extending across below the bottom wall of the 15 casing 1, at front and rear (Figs. II and IV).

As shown in Figs. I, III, and IV, the supply of liquid refrigerant (from any suitable compressor and condenser, not shown) enters through the front wall 6 of the drum 2 at 19, below the liquid level indicated by the dotted lines in Fig. IV. The refrigerant vaporized in the apparatus by the heat absorbed thereby may be withdrawn from the 25 vapor space in the upper portion of the drum 2 for return to the compressor (not shown) through any suitable connection, such as a pipe 20 (Figs. I and II).

The liquid refrigerant entering at 19 has 30 a flow toward the rear end of the drum 2, whence part of it descends through the relatively small tubes 13, 13 into the lower headers 12, 12. From these headers 12, 12, the liquid ascends through the larger tubes 35 11, 11 to the upper headers 10, 10. In the drum 2, headers 12, 12, tubes 11, 11, and headers 10, 10, the liquid refrigerant absorbs heat and vaporizes,—especially in the tubes 11, 11,—and the whole body of liquid 40 in the apparatus is thus kept at a sufficiently low refrigerating temperature. The vapor bubbles disengage from the liquid at its free surfaces in the drum 2 and the headers 10, 10. The “boiling” of the liquid in the tubes 45 11, 11 produces a ready upward flow through them, and thus effectively maintains the circulation above described. The walls of the drum 2 absorb heat from everything in the casing 1, thus maintaining an amply low 50 freezing temperature there, and the tube banks 11, 11, etc., absorb heat from the space or chamber around the apparatus, thus cooling it effectively. The absorption surfaces can easily be made of ample area, and the 55 tubes 11, 11 large enough to afford room for free circulation of liquid and vapor.

In a compression-condensation-vaporization system, suitable provision must, of course, be made for releasing the pressure 60 on the liquid refrigerant. As shown in Figs. II—IV, this is done at an automatic valve 23 located within the drum 2, and controlled by a float 24 automatically responsive to the liquid level in the apparatus. This float 65 24 is mounted on a rod 25 fixed to a part 26

pivoted at 27 between ears or lugs 28 on a part or structure 29 that will be further described hereinafter. As shown in Fig. II, the valve 23 consists of a flat-ended cylindrical piece of suitable yielding material 70 (cork) set flush in a corresponding recess in the part 26, and the refrigerant outlet or seat 30 with which this valve 23 cooperates has the form of a square-ended nipple projecting from a part of the structure 29. 75 When the liquid level in the apparatus is high enough, the yielding cork surface at 23 fits square and tight against the end of the nipple 30 and closes the latter completely against ingress of liquid. As the liquid 80 in the apparatus boils away and its level falls, the float 24 descends and opens the valve 23 away from the seat 30, thus admitting more liquid until the former level is restored. The cork surface at 23 is particularly advantageous for acting as an obturator in this fashion, maintaining a tight seal under very slight pressure from the buoyancy of the float 24.

As here shown, the valve 23 and outlet 30 are not located adjacent the front end of the drum 2, where the supply connection 19 enters, but near its rear end. From the connection 19, the liquid refrigerant passes rearward through an inner chamber 33 with- 90 in the drum 2, in the form of a large tube 95 mounted in the front wall 6 and carrying at its rear end the structure 29, which serves as a rear end closure. The supply connection 19 opens into the front end of the tube 33 at the top, and the liquid passes from the rear end of the tube 33 to the outlet 30 through a downward sloping passage 34 also open into the upper portion of the tube. The tube 33 is located in the lower portion of 100 the drum 2, so as to be substantially submerged in the liquid refrigerant in the latter when at the level normally maintained 105 by the float 24.

In its slow passage rearward through the 110 large tube 33, the liquid refrigerant (still under the relatively high pressure due to the compressor) is chilled below freezing by the liquid refrigerant (under comparatively 115 low pressure) surrounding the tube 33. Accordingly, any moisture which the refrigerant may happen to contain is frozen out and deposited in the bottom of the chamber 33 before the refrigerant reaches the passage 34 leading to the outlet 30. This entirely 120 prevents any formation of ice crystals at the valve opening 30, where the reduction in pressure takes place, and thus obviates the interference with the proper working of the valve which results from the presence of 125 such crystals at that point.

Preferably, a refrigerant is employed which does not combine with water (e. g., ethyl chloride), rather than one (e. g., sulphur dioxide) which does form such a union. 130

With such a refrigerant, moisture is effectually separated out by freezing, and is thus quite harmless.

Having thus described my invention, I 5 claim:

1. A refrigerating device of the character described comprising a cooling chamber, external banks of upright evaporating tubes against its sides, and headers above and below the upper and lower corners of said chamber connected to said tubes.

2. A refrigerating device of the character described comprising a cooling chamber, external banks of upright tubes against its 15 sides, headers above and below the upper and lower corners of said chamber connected to said tubes, and a liquid and vapor drum between the upper headers.

3. A refrigerating device of the character 20 described comprising a cooling chamber, banks of evaporating tubes at its sides, and transverse stays from bank to bank holding the banks against the chamber.

4. A refrigerating device of the character 25 described comprising a cooling chamber with trays therein, headers above the upper corners of said chamber with banks of evaporating tubes at the sides of the chamber connected to said headers, a liquid and vapor drum between said headers, and transverse stays from bank to bank below the trays and between the trays and said drum.

5. A refrigerating device of the character 35 described, comprising a cooling chamber, banks of evaporating tubes at its sides exposed to the atmosphere surrounding the refrigerating device, a drum receiving the compressed and condensed refrigerant, and downflow means outside said chamber connecting said drum to the lower portions of 40 said tube banks.

6. A refrigerating device of the character 45 described comprising a cooling chamber with a door at one end, banks of evaporating tubes at the sides of said chamber with upper and lower headers connected to their ends, a drum between the upper headers re-

ceiving the compressed and condensed refrigerant at one end of said drum, and downflow means connecting the other end 50 of said drum to the corresponding ends of the lower headers.

7. A refrigerating device of the character described comprising a drum receiving the compressed and condensed refrigerant, banks 55 of evaporating tubes at either side of said drum, and downflow means connecting said drum to the lower portions of said tube banks.

8. A refrigerating device of the character 60 described comprising banks of upright evaporating tubes with upper and lower headers connected to their ends, a drum between the upper headers receiving the compressed and condensed refrigerant, and downflow 65 means connecting said drum to the lower headers.

9. A refrigerating device of the character described comprising banks of upright evaporating tubes with upper and lower headers 70 connected to their ends, a drum between the upper headers receiving the compressed and condensed refrigerant at one end, and downflow means connecting the other end of said drum to the corresponding ends of the lower 75 headers.

10. A refrigerating device of the character described comprising a drum with a supply connection at one end for the compressed and condensed refrigerant, banks of evaporating tubes at either side of said drum, an inner chamber in said drum affording passage for the refrigerant from the end where it is supplied thereto toward the other end, with a control valve for the outlet from said 85 chamber into the interior of the drum, and means of downflow connection from the drum end toward which the refrigerant flows through said chamber to the lower portions of said tube banks. 90

In testimony whereof, I have hereunto signed my name at Buffalo, New York, this 15th day of July, 1926.

EUGENE L. BARNES.
